UNITED STATES PATENT OFFICE.

JOHN S. SKELLY, OF MONONGAHELA, PENNSYLVANIA, ASSIGNOR TO INTERNATIONAL COMBUSTION ENGINEERING CORPORATION, A CORPORATION OF DELAWARE.

UNDERFEED STOKER.

Application filed July 26, 1920. Serial No. 398,897.

To all whom it may concern:

Be it known that I, JOHN S. SKELLY, a citizen of the United States, and a resident of Monongahela, in the county of Washington and State of Pennsylvania, have made a new and useful Invention in Underfeed Stokers, of which the following is a specification.

This invention relates to furnaces and particularly to furnaces in which automatic means are employed for delivering the fuel to the furnace and for propelling it across the fuel supporting elements of the furnace.

An object of the invention is to produce a furnace of the type specified in which improved means are employed for effectively propelling the fuel rearwardly through the furnace and for effectively controlling combustion throughout different portions of the fuel bed.

A further object is to produce a furnace of the type specified, which is provided with a transversely extending retort at the front of the furnace and in which new and improved means are employed for breaking up or agitating the fuel contained within the retort, for propelling the fuel rearwardly from the retort to the ash receiving or discharging mechanism, and for controlling combustion throughout the fuel bed.

A further object is to produce an under feed stoker of improved construction in which a new and improved arrangement of fuel supporting and fuel propelling elements are employed, whereby a better distribution of fuel through the fuel bed is obtained and a better operation of the furnace is insured under widely varying operating conditions.

40 A further object is to produce an under feed stoker employing improved details of construction so combined and associated as to produce a stoker having a wide range of fuel burning capacity and one which is efficient and effective while operating under widely varying operating conditions.

These and other objects, which will be made more apparent throughout the further description, are attained by means of a stoker embodying the features herein described and illustrated in the drawings accompanying and forming a part hereof.

In the drawings, Figure 1 is a diagrammatic, longitudinal, sectional view of a stoker embodying my invention. Figures 2

and 3 are each fragmental sectional views illustrating details of construction employed in connection with a stoker such as is illustrated in Figure 1. Fig. 4 is a fragmental sectional view along the line 4—4 of Fig. 1.

The stoker illustrated is provided with a retort 5, which extends transversely across the front of the furnace and is so arranged and constructed that the fuel delivered to it is retained therein a sufficient period to occasion a partial distillation of the volatile material. It is also so arranged and constructed that the incoming fuel enters the retort below the surface of the fuel contained therein and occasions a breaking up of the mass of fuel within the retort and an upward movement of the fuel as it moves transversely across the retort and is fed onto fuel supporting elements or grate bars forming a part of the furnace structure. In the embodiment of the invention illustrated, the rear wall of the retort is, in effect, made up of the forward ends of a series of grate bars which receive the fuel as it issues from the retort. The grate bars of this series are preferably alternate moving and stationary bars, so constructed and located that the longitudinal movement of the moving bars not only occasions a breaking up of the fuel issuing from the retort, but also occasions a displacement of the fuel in such a way that combustion of the fuel leaving the retort is facilitated. In addition, the motion of the grate bars occasions or aids the propulsion of the fuel toward the rear of the furnace. The furnace also includes a second series of grate bars, which is preferably composed of alternately arranged moving and stationary bars, located

between the first series of bars and the ash or refuse receiving or discharging mechanism. As shown, the rear ends of these bars are so located and arranged that they discharge the ash or refuse material into an open well or pit which may be provided with well known clinker grinder roll or rolls or a conveyor adapted to break up and discharge the refuse material delivered to the well. The movement of the movable bars of the second series is preferably capable of adjustment, independently of the bars of the first series, as shown in my application Serial No. 330,953, filed October 16, 1919, now Patent No. 1,393,979, granted October 18,

1921, and each series is associated with independently controllable means for delivering air to the fuel bed.

Referring more particularly to the drawings: The stoker illustrated is provided with a reciprocating plunger 6 which, operating in conjunction with a hopper 7, is adapted to feed fuel from the hopper across a flat horizontal floor or plate 8. This plate 8 10 extends through the front wall of the furnace and at its inner end forms the floor of the retort 5. Any suitable means may be employed for reciprocating the plunger 6, and in the drawings I have diagrammatically illustrated a mechanism 6' for accomplishing this. The fuel fed across the plate 8 by the plunger 6, traverses a gradually expanding passage 9 as it enters the retort. This passage is formed between 15 the plate 8 and an upwardly and rearwardly inclined plate 10, which, as illustrated, forms a support for the upper portions of the front wall of the stoker.

The retort 5 is adapted to deliver fuel 20 onto a series of alternately arranged moving and stationary grate bars 11 and 12. The grate bars of this series are located side by side and extend downwardly in parallel relation toward the rear of the furnace.

25 As shown, the forward end of each grate bar is supported on the rear edge of the plate 8, whereas, the rear end is supported on a bracket 12^a, which forms a part of the frame work of the stoker structure.

30 As has been said, the forward ends of the grate bars 11 and 12, in effect, form the rear wall of the retort 5. The bars are so located and arranged that the fuel in leaving the retort must pass upwardly over 35 the forward ends of the bars as it moves onto the fuel supporting surfaces thereof. This rearward movement of the fuel is facilitated by a periodic longitudinal motion of the moving grate bars 11.

40 As shown, each of the moving grate bars is provided with a bearing surface 13 at its forward end and a corresponding bearing surface 14 at its rear end. These surfaces are so located with relation to the 45 major axis of the bar that they are substantially horizontal when the bar is mounted in place on the frame of the stoker structure. With this arrangement, the reciprocations of the bar are such that each

50 point of the bar moves substantially horizontally. Consequently, the forward end of the bar is pushed substantially horizontally into the mass of fuel contained within the retort during each forward reciprocation and is then withdrawn horizontally away from and even out of the confines of the retort, as defined by the forward faces of the stationary bars. For 55 the sake of simplicity of manufacture and

60 standardization of parts, the stationary

bars, are substantially similar to the moving bars, except that each stationary bar is provided at its forward end with downwardly projecting lugs 15, which engage opposite sides of a transversely extending flange 16 formed on the rear edge of the plate 8. (See Fig. 2.) As shown, the forward end of each moving and stationary grate bar is wedged shaped with the apex of the wedge located adjacent to the upper surface of the plate 8. With this arrangement, a forward movement of the moving bars into the mass of rearwardly moving fuel within the retort 5 breaks up the mass by causing portions thereof to move upwardly across the inclined forward face of the bar and onto the bar. This motion of each bar also advances the position of the fuel bed proper with relation to the forwardly moving grate bars and causes an agitation of the fuel bed, since the forward movement of the bar causes its rearwardly inclined, fuel supporting surface to, in effect, move out from under or away from the fuel supported by it. This occasions settling of the fuel bed to fill the space vacated by the forwardly moving bars, and as these bars move rearwardly, they positively displace the portion of the fuel bed supported by them, by carrying it toward the rear of the furnace and at the same time move it upwardly with relation to the portions of the fuel bed supported by the stationary bars. As the forward ends of these moving bars move out of the mass of partially coked fuel contained within the retort 5, they occasion a settlement of the mass of fuel and a consequent agitation and breaking up of the mass contained within the retort. It will, therefore, be apparent that the fuel contained within the retort and the fuel located on the grate bars is positively broken up by the reciprocations of the moving bars, and at the same time is positively propelled toward the rear of the furnace.

65 As shown in Figure 1, the moving bars are actuated by means of a rocker bar 17, which extends transversely of the grate bars 11 and 12 and is mounted in suitable bearings supported by the supporting frame of the stoker and located substantially midway between the ends of the bars 11 and 12. As illustrated, the rocker bar 17 is provided with a longitudinally extending rib 18, which projects upwardly and is adapted to be engaged by lugs 19 formed on the lower faces of the moving grate bars 11. The rocker bar 17 is preferably oscillated by means of the actuating mechanism of the plunger 6, as clearly illustrated in my patent, aforesaid.

70 As shown, the bars 11 and 12 of the first series are adapted to feed fuel onto a second series of alternately arranged moving and

stationary bars 21 and 22. The bars 21 and 22 extend rearwardly of the furnace and are located side by side. The forward end of these bars preferably projects under the rearwardly projecting ends of the bars 11 or 12 of the first series and the upper face of each bar 21 and 22 may be engaged by the horizontally disposed bearing surface 14 of the bar under which it projects. Each of the bars 21 and 22 is so formed that the fuel supporting surface at the end of the bar adjacent to the first series extends at such an angle to the major portion of the fuel supporting surface that it occupies a horizontal position when the grate is in place on the supporting structure; whereas, the major portion of the fuel supporting surface is inclined downwardly toward the rear of the furnace. Each grate bar of this series is also provided with front and rear bearing surfaces 23 and 24, so inclined with relation to the longitudinal axis of the bar that they occupy substantially horizontal positions when the bar is in place on the supporting structure. With this arrangement, the moving bars move horizontally, as described in connection with the bars 11 and 12. This motion is imparted to them by a rocker bar 25, which is illustrated as extending transversely of the bars and located intermediate their ends. The mechanism for actuating the rocker bar 25 and the operating connections between it and the moving bars 21 may be substantially as illustrated in my before mentioned copending application.

For convenience in manufacture, the stationary and moving bars 21 and 22 are substantially similar in details of construction, except that each stationary bar is provided with lugs 26 and 27 which engage the top flange of a partition 28 on which their lower ends are supported. (See Fig. 3.) As shown, each bar is hollow, having a passage 30 extending from the forward to the rear end thereof. An air admission port 31 is formed in the bottom face of each bar adjacent the forward end thereof, and an air discharge port 32 is formed in the bottom face adjacent the rear end thereof. Air delivery ports 33 are formed in the fuel supporting surface of each bar and are located on the forward portion of the bar. All these ports communicate with the interior passage 30. The forward end of each bar is shown as rectangular in vertical section, that is, the forward end face extends substantially at right angles to the adjacent portion of the top and bottom surfaces of the bar. The rear end of each bar is similarly constructed, except that the upper edge projects beyond the lower edge.

As shown, the bars 21 and 22 partially overhang a well or pit 34 formed between the bridge wall 35 and the partition 28. In

the drawings, I have diagrammatically illustrated a refuse crushing and discharging mechanism 34^a, which may be continuously or periodically operated for the purpose of crushing and discharging such ash and refuse material as collects in the well 34.

One of the features of this invention is the means employed for delivering air under pressure to the incoming fuel and the fuel supported by the grate bars. As illustrated, the space below the grate bars is divided into separate fuel delivery passages in order that the air supply to the furnace may be more readily controlled for the purpose of maintaining the desired condition of combustion throughout the entire fuel bed. As illustrated, a passage 36 is located between the front wall 37 of the furnace and a plate 38, which extends upwardly from the bottom of the furnace structure to a suitable bracket 39^a forming a part of the frame work of the stoker. This passage 36 communicates directly with an air duct 39, which may receive air under pressure from a fan or blower. The bracket 39^a extends transversely of the grate bars 11 and 12, and with the front plate 37 or an auxiliary plate secured thereto forms a passage which extends transversely of the grate bars and communicates with the air admission ports 40 of the grate bars. The space located below the grate bars and between the plate 38 and a partition wall 41, forming a part of the frame work of the stoker, is what may be termed a secondary air chamber, since it receives air from the air delivery passages 42 through discharge ports 43 of the grate bars and delivers it to the fuel bed through the spaces between the adjacent grate bars 11 and 12.

For the purpose of supplementing this air supply in such a way that the thicker portion of the fuel bed receives a greater quantity of air under pressure than the thinner portions, I have provided ports 47 in the fuel supporting surface of each grate bar adjacent the forward end of the bar. These ports 47 communicate with the interior passage 42 and are so arranged that some of them deliver air to the fuel issuing from the retort 5 and moving up the wedge shaped ends of the bars; whereas, some of them deliver air to the fuel located on the forward portion of the downwardly inclined supporting surface of the bar. With this arrangement, the fuel bed receives air which has traversed the passages 42 of the grate bars and the air chamber 44, and a portion of the fuel bed also receives air directly from the passages 42. The same is true of the fuel issuing from the retort, since the spaces between the grate bars permits some air under pressure to pass into the retort from the secondary air chamber 44 and also from the passage 36. In addition, the fuel issuing

from the retort also receives air from the ports 47 located in the wedge shaped forward end of each bar.

Inasmuch as the forward ends of the bars 11 and 12 act as a deflector, the fuel bed supported by these bars will be thickest at points adjacent to the forward ends of the bars and as a result, this thick portion will require a greater amount of air than the thinner portions of the bed and can be supplied with a greater amount of air without danger of blowing holes in the fuel bed and thereby cutting down the efficiency of the furnace. In the stoker illustrated, combustion is accelerated as the fuel issues from the retort by the arrangement of the grate bars with relation to the retort and also by the arrangement of the air admission passages for delivering air to the retort and that portion of the fuel bed immediately adjacent the retort. As previously pointed out, the movement of the moving grate bars agitates and breaks up the mass of fuel issuing from the retort, and this agitation is continuously taking place due to the periodic action of the moving grate bars and the fuel feeding plunger. As a result, the air admitted to the forward portion of the fuel bed is highly effective in supporting combustion and the mass of fuel within the retort proper is, therefore, subjected to the sensible heat of a mass of vigorously burning fuel immediately adjacent the retort. This feature I believe is new, since so far as I know, no stokers now on the market supply air in the manner above described, to an agitated portion of the fuel bed located immediately adjacent to the retort. As a result of this method of operating the stoker, the partial coking of the fuel contained within the retort is more effectively accomplished with my stoker than with others known to me, and the partial volatilization of the fuel takes place immediately adjacent to an extremely hot and vigorously burning portion of the fuel bed. These distillates are also thoroughly mixed with the excess air delivered through the ports 47 and through the spaces between the grate bars. It will, of course, be understood that any excess air so delivered to the distillates is highly heated by its passage through the incandescent and vigorously burning fuel and that consequently, the distillates will be thoroughly consumed as they pass backwardly through the combustion chamber to the stoker.

Another feature of my invention is that the forward portions of the grate bars 11 and 12 or those portions which support the vigorously burning part of the fuel bed, receive the largest amount of air and are consequently adequately cooled. In the first place, the air traversing the longitudinal passage 42 takes up heat from the grate bars

and this heat is subsequently returned to the fuel bed. The heat transfer from the grate bars to the air traversing them results in a cooling of the grate bars. It will be apparent that the volume of air traversing the forward portion of each grate bar is materially greater than the volume traversing the remainder of the grate bar; consequently, the air traversing the forward portions of the individual grate bars has great heat absorbing capacity and is capable of keeping the forward ends of the grate bars cool under the extreme conditions of combustion encountered. From the foregoing, it will be apparent that the greatest cooling action is encountered at the portion of each grate bar most likely to be burned away and consequently, the life of the bar is materially increased.

Substantially the same conditions exist at the forward ends of the second series of grate bars. In the drawings, I have shown the lower ends of the bars 11 and 12 so formed that the moving bars, in effect, act as pushers in propelling fuel across the bars 21 and 22. This pusher action, accomplished as it is by a horizontal reciprocation of the moving bars 11, tends to cause the fuel bed to thicken at the forward ends of the bars 21. This thickening tendency is augmented by the fact that the forward ends of the fuel supporting surfaces of the bars 21 and 22 are substantially horizontal. Consequently, it is desirable to supply sufficient air to the fuel bed at this point to insure thorough combustion from the front to the rear end of the bed. This is accomplished by providing the ports 33 in the bars 21 and 22 and by locating these ports in the forward ends of the bars.

As has been described, the bars 21 and 22 are hollow and are provided with ports 31 and 32. As shown, the ports 31 receive air from a passage 50, which extends upwardly from the floor of the furnace structure and is located between suitably positioned partition plates 51 and 52. This passage also communicates directly with an air duct 53, which may receive air from the duct 39 or from a separate source of supply. If the duct 53 receives air from the duct 39, it is desirable to employ a damper or other controlling means in the duct 53, so that the supply of air through the passage 50 may be regulated independently of the supply of air through the passage 36.

The passage 50, like the passage 36, extends transversely of the grate bars associated with it and delivers air to the ports 31 of those bars. A portion of the air so delivered traverses the passages 30 of the grate bars and is received by a secondary air chamber 53, located below the major portion of the bars 21 and 22. This air is heated in its passage through the grate bars

and in the preheated state is delivered to the fuel bed through the spaces between the grate bars. Under such conditions, substantially all of the fuel bed supported by the grate bars 21 and 22 receives preheated air from the secondary air chamber 53; whereas, that portion of the fuel bed located immediately adjacent to the first series of bars also receives air direct from the ports 33.

Even though the arrangement and the operation of the grate bars may not occasion a thickening or a material thickening of the fuel bed at the forward ends of the bars 21 and 22, it is desirable to accelerate combustion at this point by the breaking up of the fuel bed and by the delivery of adequate quantities of air to support vigorous combustion. It will be apparent that the fuel, after having traversed the bars 11 and 12, is comparatively low in combustible material; consequently, it is desirable to maintain, if possible, a hot zone through which this fuel must pass before being delivered to the ash pit or well 34. By providing this hot zone in which combustion is a second time accelerated, I am able to maintain combustion throughout substantially the entire fuel bed and to deliver ash and refuse material in which the carbon content is exceedingly low.

In the drawings, I have illustrated separate doors 55 and 56 which give access to the respective chambers 44 and 53 for the purpose of removing siftings from these chambers.

The operation of the furnace illustrated is briefly as follows: The hopper 7 is filled with fuel, which is fed across the plate 8 and into the retort 5 through the rearwardly expanding passage 9. This passage 9 is preferably so designed that it permits the coal traversing it to form a seal between the interior and the exterior of the stoker, but it is also so formed that it prevents packing of the coal and a resultant detrimental effect on the operation of the stoker. It will be noted that the inclination of the bars 21 and 22 is somewhat less than the inclination of the bars 11 and 12. This maintains a thicker fuel bed throughout than would be the case if the bars 21 and 22 were inclined the same amount as the bars of the first series. The fact that a relatively thick fuel bed is maintained from the front to the rear of the furnace enables the furnace to be operated under higher conditions of air pressure than would be the case if the fuel bed thinned out toward the rear. As a result, the stoker may be operated under high capacities by speeding up the fuel feeding mechanism and the moving grate bars and by increasing the blast or forced draft to the fuel bed. The air supply to the portion of the fuel bed supported by the grate

bars 21 and 22 may also be controlled independently of the air supply to the remaining portion of the fuel bed, and in this way, the combustion throughout the entire bed may be controlled and a hot zone may be attained at a point substantially midway between the front and rear ends of the stoker.

For this purpose I may employ a damper 53a in the air duct 53.

It will, of course, be understood that while I have illustrated but one plunger 6, and hopper 7, several plungers and co-operating hoppers may be employed to feed fuel into the retort 5. It will also be understood that the grate bars of the two series may be divided into groups and that the moving bars of each group may be operated independently of the moving bars of the other groups, and independently or in connection with the fuel feeding mechanism of these groups.

While I have illustrated and described but one embodiment of my invention, it will be apparent to those skilled in the art that various changes, modifications, additions, omissions, and substitutions may be made in the apparatus illustrated without departing from the spirit and scope of the invention as set forth by the appended claims.

What I claim is:

1. In combination in a furnace, a fuel feeding mechanism, a floor across which fuel fed by said mechanism is moved, a series of grate bars extending longitudinally of the furnace and associated with said floor to form a retort extending transversely across the front of the furnace, a second series of grate bars onto which fuel moves from the first series, a bridge wall spaced from the second series of bars to form an ash receiving well, and means for imparting a fuel impelling motion to grate bars of both series.

2. In combination in a furnace, a fuel feeding mechanism, a floor across which fuel fed by said mechanism is impelled, a series of alternately arranged moving and stationary grate bars, associated with said floor to form a retort at the front of the furnace, a bridge wall, a second series of alternately arranged stationary and movable grate bars between said bridge wall and said first series and spaced from the bridge wall to form an ash receiving well into which fuel impelled across said second series of bars is discharged, and means located in the bottom of said well for discharging the ash and refuse mechanism received thereby.

3. In combination in a furnace, a fuel feeding mechanism, a floor across which fuel is fed by said mechanism, a series of downwardly inclined hollow grate bars having wedge-shaped forward ends associated with said floor to form a coking retort at the front of the furnace, and having aper-

- tures formed in the wedge-shaped ends thereof and in the fuel supporting surface thereof intermediate the ends of the bars for delivering air from the interior of 5 the bar to fuel issuing from said retort and fuel located on said bars, a second series of hollow grate bars located below and extending rearwardly from said first series, and having apertures formed in the fuel sup- 10 porting surfaces thereof adjacent said first series of bars for delivering air to the fuel received from said first series of bars and means for delivering air under pressure to said bars.
- 15 4. In combination in a furnace, a fuel feeding mechanism, a floor across which fuel is fed by said mechanism, a series of alternately arranged downwardly inclined moving and stationary grate bars, associated 20 with said floor to form a retort at the front of the furnace, a bridge-wall, a second series of alternately arranged downwardly inclined stationary and moving grate bars between the bridge-wall and the first series. 25 and spaced from the bridge-wall to provide an ash receiving well, the inclination of the second series being less than that of the first series and means for delivering unheated and pre-heated air to the fuel supported 30 by both series of bars.
- 35 5. In combination with a furnace, a stoker comprising a retort extending across the front of the furnace, a downwardly inclined series of spaced, alternately arranged, mov- 40 able and stationary grate bars extending in parallel relation from said retort toward the rear of the furnace, each bar provided with a wedge shaped forward end and having air delivery apertures in its wedge shaped forward end and in its upper face intermediate its ends, a second series of spaced, down- 45 wardly inclined, alternately arranged, movable and stationary grate bars, extending in parallel relation from the rear ends of said first series toward the rear of the furnace, 50 each bar provided with air delivery apertures in its upper face intermediate its ends and means for forcing air under pressure through the apertures of said bars and through the spaces between the bars. 55
6. In combination in a stoker, a retort extending transversely across the front of the stoker, means for feeding fuel into and transversely across the retort, a series of alternately arranged, moving and stationary 60 air delivering grate bars located in parallel relation and extending from the retort toward the rear of the furnace and so arranged that the forward ends of the bars form an extension of the fuel delivery side 65 of the retort and the moving bars move into and out of the confines of the retort as defined by the forward ends of the stationary bars, each bar having air delivery apertures formed in the forward end of the fuel supporting surface thereof, a second series of alternately arranged, moving and stationary air delivering grate bars, located in parallel relation, overlapped by the first series, and extending toward the rear of the fur- 70 nace, each of said second series of bars having apertures formed in the forward end of the fuel supporting surface thereof and means for delivering air under pressure through the bars of both series and through 75 said apertures for maintaining zones of increased combustion adjacent to the forward ends of the bars of each series.

In testimony whereof, I have hereunto subscribed my name this 22 day of July, 1920.

JOHN S. SKELLY.
